(57) **CLAIM**

The ornamental design for a dog bone shaped spacer exercise device, as shown and described herein.

DESCRIPTION

FIG. 1 is a perspective view of my new dog bone shaped spacer exercise device.

FIG. 2 is a front view of my new dog bone shaped spacer exercise device.

FIG. 3 is a back view of my new dog bone shaped spacer exercise device.

FIG. 4 is a right side view of my new dog bone shaped spacer exercise device.

FIG. 5 is a left side view of my new dog bone shaped spacer exercise device.

FIG. 6 is a top view of my new dog bone shaped spacer exercise device; and,

FIG. 7 is a bottom view of my new dog bone shaped spacer exercise device.

1 Claim, 7 Drawing Sheets
